UNITED STATES PATENT OFFICE.

WILLIAM BARDSLEY, OF KEARNEY, NEW JERSEY.

ELEVATOR-SHAFT AND DOORS THEREFOR.

1,095,370.

Specification of Letters Patent.

Patented May 5, 1914.

Application filed November 21, 1911. Serial No. 661,475.

To all whom it may concern:

Be it known that I, WILLIAM BARDSLEY, a citizen of the United States, and a resident of Kearney, in the county of Hudson and State of New Jersey, have invented certain new and useful Improvements in Elevator-Shafts and Doors Therefor, of which the following is a specification.

The invention relates to improvements in the character of elevator shafts and doors therefor common to factory and loft buildings, and it consists in the novel features, structure and combinations of parts herein-after described, and particularly pointed out in the claims.

In the preferred embodiment of my invention I provide the elevator shaft or well at each floor of the building with two vertically movable fire doors or a door in two sections, one opening upwardly and the other downwardly, said doors having means for compelling simultaneous movement thereof in opposite directions and the upper door being heavier than the lower door, so that when the doors are released to close, they will automatically move to their closed position. In accordance with my invention I provide means for automatically locking the doors in their open position and of releasing said doors to automatically close when the car leaves the floor at which the doors may have been opened, and I also provide means whereby should the car be left at a floor for the night or other period and the doors thereat carelessly left in their open position, said doors will be released in the event of a fire taking place, to close, a fusible member being provided in the locking mechanism to melt in the event of fire and permit the release of the doors to close automatically. I also provide the doors with means for cushioning their action, thereby avoiding slamming and consequent accidents, and also with special means for suspending the lower door in such manner that its upper edge will, when the doors are open, be in line with the floor of the building and the floor of the elevator car, so that as little space as possible may be left between the floor of the building and the car.

The invention will be fully understood from the detailed description hereinafter presented, reference being had to the accompanying drawings, in which:

Figure 1 is an elevation of a pair of self-closing fire doors and a portion of the ele-

vator shaft or well equipped with the features of my invention, the view being taken from the inner side of the shaft or well and looking at the rear faces of the doors, which in Fig. 1 are shown in their open position, Fig. 2 is a vertical section of the same on the dotted line 2—2 of Fig. 1, with a portion of the car or hoist in position at one floor and in line with the opening between the two doors or door sections; Fig. 3 is a horizontal section through the same on the dotted line 3—3 of Fig. 2; Fig. 4 is an enlarged view of the devices for locking the upper door in its upper position; Fig. 5 is a horizontal section of the same on the dotted line 5—5 of Fig. 4; Fig. 6 is a vertical section of the same on the dotted line 6—6 of Fig. 4, and Fig. 7 is an enlarged vertical section of the cushioning devices for cushioning and controlling the action of the doors.

In the drawings, 10 designates a portion of an elevator shaft or well, 11 a portion of an elevator car or hoist therein, 12 one of the floors of the building, 13 a door-way leading from a loft or room possessing said floor to the car, 14 an upper sliding door or door section, and 15 a lower sliding door or door section, said sections being shown in their open position in Figs. 1 and 2 and being adapted to move vertically toward and from each other for controlling said door-way 13. The door sections 14, 15 are provided with laterally projecting flanges or the like 16 adapted to the guides 17 which are fastened to the wall of the building and serve to confine and direct the door sections 14, 15 in their movements toward and from each other. The flanges 16 and guides 17 may be of any suitable form and construction. The door sections 14, 15 are shown in their open position fully exposing the door-way 13, but when said sections are moved toward each other, they meet at about the transverse middle portion of the door-way 13 and fully close the latter.

The door-sections 14, 15 may be made of any suitable material, but I preferably make them of fire proof material or of wood covered with sheet iron.

The door sections 14, 15 are connected together at each side of the elevator-shaft by means of ropes or cables 18 which pass over pulleys 19 mounted in the shaft, said cables being connected at their upper ends with a bar 20 constituting the lower edge of the door section 14 and at their lower ends to a

bar 21 constituting the upper edge of or secured to the door section 15. The connecting cables or ropes 18 assure simultaneous movement in the door sections 14, 15 toward and from each other, any upward movement of the door section 14 acting to pay out the cables 18 over the pulleys 19 and allowing the lower door section 15 to descend, and any downward movement of the door section 15 acting to draw on the cables 18 and thereby elevate the door section 14. The upper door section 14 is heavier than the lower door section 15, and this is for the purpose of compelling an automatic movement of the door sections, when they are released, to their closed position.

When the door sections 14, 15 are opened by an attendant on the elevator hoist or car 11, they should remain open so long as the elevator car is at the floor 12 and should automatically close when the car 11 leaves said floor, and to these ends I provide means for locking the doors in their open position and of releasing the locking means when the car 11 leaves the floor 12. The means provided for locking the doors 14, 15 in their open position may comprise a latch 22 pivotally mounted in a slot in the door section 14 and provided with a spring 23 tending to turn said latch outwardly toward the elevator shaft or well 10, a bar 24 to be engaged by said latch 22 and a spring-bar 25 to which said bar 24 is secured and which is secured at its lower end by rivets or the like 30 to a stationary part of the building structure. The bar 25 has a spring tension normally holding its upper portion sufficiently inwardly from the car door for the bar 24 to normally stand free of the path of the projecting portion of the latch 22. The spring-bar 25 is restrained as to its outward movement in a direction from the vertical plane of the doors by means of an angular bracket 27, and the lower portion of said bar 25 is formed with a bulged or cam portion 28, the latter being directly in the vertical path of a cam 29 secured upon the car 11 in line with the spring-bar 25. When the car 11 arrives at a floor of the building, the cam 29 40 by pressing against the protruding portion 28 of the bar 25 will cause said bar to move inwardly and position the bar 24 for engagement with the spring latch 22, and when the car 11 leaves the floor of the building, moving either upwardly or downwardly, the cam 29 will be carried from the projecting portion 28 of the bar 25 and will thereby release said bar and permit it of its own flexure to spring outwardly from the doors and 50 into the well or shaft 10 as far as the bracket 27 may permit, and thus carry the bar 24 from engagement with the latch 22, thereby releasing the doors and permitting them to automatically move to their closed position. 55 The spring latch 22 is restrained by a shoul-

der 30 from moving unduly outwardly, and is formed with a shoulder 31 to engage the bar 24 when the latter is held inwardly at its operative position, shown in Fig. 6, by the engagement of the cam 29 on the car 70 with the projecting portion 28 on the bar 25. The bar 24 thus normally stands free of the latch 22 and is positioned to be engaged by said latch by the car when arriving at a floor of the building. The bar 24 will preferably 75 be pivotally secured to the bar 25 and provided with a spring 32 normally acting to pull it downwardly toward a parallel position with the bar 25, and the action of the spring 32 is restrained by means of a link 80 33 extending from the upper portion of said bar 24 to the upper portion of the bar 25 and containing a fusible element 34 which will melt in the event of a fire taking place in the building and reaching said link. 85 Under normal conditions the bar 24 will stand at right angles to the bar 25, as shown in Fig. 4, with the spring 32 exerting its force to turn said bar downwardly and with the link 33 restraining the action of the 90 spring 32 and maintaining said bar in a horizontal position. The spring 32 is only permitted to act to pull the bar 24 downwardly when the fusible member 34 melts, and the presence of the spring 32 and link 33 is advantageous more particularly to enable the automatic closing of the door-sections 14, 15 in the event that the car 11 should be left at a floor of the building for the night or other period and the doors thereat carelessly left 100 in their open position. In the event of a fire it is desirable that the elevator shaft should be closed, and the means I have provided to-wit: the spring 32 and link 33 co-acting with the bar 24 will insure the release of the doors to close in the event that they should have been left open and that a fire should take place.

The movement of the door sections 14, 15 should be so controlled that the upper edge 110 of the lower door section will be about on a level with the floor 12 and the floor of the car 11 when the said sections are in their open position, and while I do not limit the entire invention to any special means for 115 thus limiting the movement of the doors, since the control of the movement of either door-section will govern the movement of the other door-section, I preferably connect the upper edge of the lower door section or 120 the ends of the bar 21 thereon with strong chains 35, whose upper ends are fastened to a stationary portion of the building structure and which chains are of such length that upon the opening of the lower door section 15 they will stop and suspend the same when the bar 21 is on a level with the floor 12.

In order to prevent any slamming of the door sections 14, 15 and thereby to avoid ac- 125 130

5 cidents, noise and wear on the door connections, as well as the doors themselves, I provide cushioning means preferably comprising air cylinders 36 secured to the wall of the shaft and each containing a piston 37 and projecting piston-rod 38, the latter preferably having coiled upon it a spring 39 acting to move the piston-rod to its outer or exposed position. The cylinders 36 and 10 piston-rod 38 are in the path of buffers 40 secured on the projecting end portions of the bar 21 carried by the lower door section 15. When the door sections 14, 15 move toward their closed position or toward each other, 15 the buffers 40 will strike the piston-rod 38 and drive the pistons 37 upwardly into the upper portions of the cylinders 36, wherein the air will be trapped and act as a cushion to prevent the violent meeting of the 20 door sections 14, 15, without however interfering with said sections coming together. The cushioning of the sections 14, 15 is effected by the air trapped in the upper ends of the cylinders 36 during the closing movements 25 of said sections and also partly by the springs 39. After the door sections 14, 15 are moved to their opened position, the air will leak from the cylinders 36 and the pistons 37 and piston-rod 38 will automatically 30 descend to their lower position, being assisted in such movement by the springs 39. I provide within the upper ends of the cylinders 36 a cushioning block 41 against which the central portions of the pistons 37 35 may move, and in the lower ends of the cylinders 36 I provide a disk or block of cushioning material 42 to receive the lower end of the pistons when the latter descend to their lower position. In the present instance 40 I have the piston-rod 38 projected downwardly so as to be driven upwardly by the lower door section 15, but obviously the cylinders 36 may be turned upside down and said rods 38 operated from the upper door 45 section 14. I have also in the present instance extended the cables or ropes 18 downwardly through the cylinders 36 and piston-rod 38, but it is to be understood that said cables or ropes do not constitute any direct 50 portion of the cushioning devices, since said devices would perform just exactly the same function if the ropes or cables 18 extended along the sides of instead of through said cylinders. It is convenient in the matter of 55 economizing space to extend the ropes or cables 18 lengthwise through the cylinders 36.

60 The operation of the door sections 14, 15 and parts connected therewith will be understood without much further detailed description. It may be said, however, that upon the car 11 arriving at a floor of the building, the cam 29 thereon by engaging the spring bar 25 will move the latch-bar 24 inwardly toward the vertical plane of the up-

per door section 14, and that the operator on the car will open the doors by hand, preferably by pushing the upper door section upwardly. Upon the upper door section 14 reaching its upper position, the latch 22 70 will have traveled behind the latch-bar 24 and will spring outwardly above said bar, or to the position shown in Figs. 4 and 6, and by its engagement with said bar will support the upper door section in its open 75 position and through the cables or ropes 18 aid in suspending the lower door section 15 in its open position. Upon the car 11 leaving the floor at which the door sections were opened, the cam 29 on the car will release the spring bar 25 and the latter will move the latch-bar 24 from below the latch 22, and thereupon the door-sections 14, 15 will automatically close, their closing movement being cushioned by the air trapped 80 within the cylinders 36. When the lower section 15 is in its open position, the chains 35 will suspend it firmly so that it may fully resist any pressure which may be exerted against its upper edge when said edge 85 is in line with the floor 12. Should the door sections 14, 15 be left open through carelessness or otherwise and a fire should take place, the fuse 34 will melt and the spring 32 will then turn the bar 24 downwardly 90 from the latch 22 and enable the door sections 14, 15 to close automatically, the upper door section being heavier than the lower door section and compelling an automatic closing of the doors when the latch 95 22 is free of the bar 24. The upper door section 14 being heavier than the lower door section 15 overbalances said lower door section, but I do not limit my invention to this precise arrangement since the automatic 100 closing of the door-sections may be attained in other ways, as, for instance, the lower door section may be overbalanced by weights and ropes, such as are commonly used on ordinary window sashes, to automatically move it to its closed position and enable it, through the ropes, chains or cables 18, to move the upper door section 14 to its closed position.

105 By the terms door and door-sections as employed herein I mean to include both fire-proof and non-fire-proof doors and door sections and doors and door sections made of slats or pickets and commonly called gates.

110 What I claim as my invention and desire to secure by Letters Patent, is:

115 1. Elevator shaft mechanism comprising a vertically slidable door for the entrance from a floor of a building to a car in said shaft, a latch carried by the door, a bar to be engaged by said latch when said door is moved to its open position for holding the door open, means normally holding said bar 120 out of the vertical plane of said door, and

means on the car for moving said bar in the vertical plane of said latch and there maintaining it when the car is at rest at a floor of the building, combined with the 5 car and means for effecting the disengagement of said bar and latch in case of fire to permit said door to move to its closed position.

2. Elevator shaft mechanism comprising 10 a vertically slidable door for the entrance from a floor of a building to a car in said shaft, a latch carried by the door, a bar to be engaged by said latch when said door is moved to its open position for holding 15 the door open, means normally holding said bar out of the vertical plane of said latch, and means on the car for moving said bar in the vertical plane of said latch and there maintaining it when the car is at rest at a 20 floor of the building, combined with the car and means for effecting the disengagement of said bar and latch in case of fire to permit said door to move to its closed position and comprising a fusible member holding 25 said bar in a normal position and a spring having a tension against said bar to move it to an inoperative position when not restrained by said fusible member.

3. Elevator shaft mechanism comprising, 30 in combination, a car in the shaft, a vertically slidable door for the entrance from a floor of a building to the car in said shaft, a latch carried by the door, a bar to be engaged by said latch when said door is moved to its open position for holding the 35 door open, and means for effecting the disengagement of said bar and latch in case of fire to permit said door to move to its closed position.

4. Elevator shaft mechanism comprising, 40 in combination, a car in the shaft, a vertically slidable door for the entrance from a floor of a building to the car in said shaft, a latch carried by the door, a bar to be engaged by said latch when said door is moved to its open position for holding the 45 door open, and means for effecting the disengagement of said bar and latch in case of fire to permit said door to move to its 50 closed position and comprising a fusible member holding said bar in a normal position and a spring having a tension against said bar to move it to an inoperative position when not restrained by said fusible 55 member.

5. Elevator shaft mechanism comprising door sections vertically slidable toward and

from each other for the entrance from a floor of a building to a car in said shaft, flexible means connecting said door sections 60 for enabling their simultaneous movement, a latch carried by the upper door section which is heavier than the lower door section, a bar to be engaged by said latch when the door sections are moved to their open 65 position for holding them open, means normally holding said bar out of the vertical plane of said latch, and means on the car for moving said bar in the vertical plane of said latch and there maintaining it when 70 the car is at rest at a floor of the building, combined with the car and means for effecting the disengagement of said bar and latch in case of fire to permit said door sections 75 to automatically move to their closed position and comprising a fusible member holding said bar in a normal position and a spring having a tension against said bar to move it to an inoperative position when not restrained by said fusible member. 80

6. Elevator shaft mechanism comprising, in combination, a car in the shaft, door sections vertically slidable toward and from each other for the entrance from a floor of a building to the car in said shaft, flexible 85 means connecting said door sections for enabling their simultaneous movement, means for holding said sections in their open position, and flexible means connected with the lower door section for suspending it when 90 in its open position with its upper edge about on a level with said floor.

7. Elevator shaft mechanism comprising, in combination, a car in the shaft, door sections vertically slidable toward and from 95 each other for the entrance from a floor of a building to the car in said shaft, flexible means connecting said door sections for enabling their simultaneous movement, means for holding said sections in their open position, and chains secured at their upper ends 100 to the building structure and at their lower ends to said lower door section for suspending said section when in its lower 105 position with its upper edge about on a level with said floor.

Signed at New York city, in the county of New York, and State of New York, this 18th day of November A. D. 1911.

WILLIAM BARDSLEY.
